Primary Examiner — Susan Bennett Hattan*Assistant Examiner* — Rebecca Tsehay(74) *Attorney, Agent, or Firm* — Law Office of Dorian Cartwright; Dorian Cartwright**CLAIM**

The ornamental design for modular planter, as shown and described.

DESCRIPTION

FIG. 1 is a perspective, bird's eye view of an interlocking modular planter.

FIG. 2 is a side view of an interlocking modular planter.

FIG. 3 is a side view of an interlocking modular planter, that is rotated relative to FIG. 2.

FIG. 4 is a side view of an interlocking modular planter, that is rotated relative to FIG. 3.

FIG. 5 is a side view of an interlocking modular planter, that is rotated relative to FIG. 4.

FIG. 6 is a top view of an interlocking modular planter.

FIG. 7 a bottom view of an interlocking modular planter.

FIG. 8 a top view of an interlocking modular planter being interlocked with other interlocking modular planters.

FIG. 9 a side view of an interlocking modular planter being interlocked with other interlocking modular planters; and,

FIG. 10 a top view of an interlocking modular planter being interlocked with other interlocking modular planters, to form a circular shape.

The broken lines in the drawings depict environment that forms no part of the claimed design.
